UNITED STATES PATENT OFFICE.

CLIFTON FON KNIGHT AND GEORGE P. O'ROURKE, OF DALLAS, TEXAS.

BUILDING CONSTRUCTION FOR EXCLUDING MOISTURE.

Application filed January 18, 1926. Serial No. 31,913.

This invention relates to improvements in wooden ceiling 9 is shown instead of the building construction and it relates more particularly to the novel features thereof.

An object of the invention is to provide an insulating means for cold storage plants or buildings utilized for that purpose to increase the efficiency thereof by preventing moisture from entering the building or plant.

Another object of the invention is to provide such an insulating means for all types of buildings, particularly those of concrete and mill construction formation.

A further object of the invention is to provide a moisture insulating means which permits a continuous and unbroken layer or layers of insulating material to extend from the bottom to the top of the building and entirely enclosing each floor or story.

The invention may be thoroughly understood from a perusal of the following description taken in connection with the accompanying drawings and wherein—

Figure 1 is a vertical detail sectional view of a concrete wall with floors and ceilings and illustrating an embodiment of the invention.

Figure 2 is a similar view and illustrating an embodiment of the invention in a building of mill constructed material, and

Figure 3 is a partial horizontal sectional plan view of Figure 1.

In carrying out the invention, after the concrete floor 1 is placed and hardened and the outside walls 2 built up, several layers 35 or if preferred one layer, of the material comprising the insulating medium are laid in position, one upon the other upon the concrete. This insulating medium or material is preferably of felt, but may be of any 40 suitable material to trap the moisture. The insulating medium is then placed next the walls 2 and held in place in any suitable manner. The inner wall facing material 4 is then placed in position, and the concrete 45 flooring 5 laid upon the insulating medium. 3. The floor covering 6 may then be laid. The floor-supporting columns are indicated 50 at 7 and 8 denotes one of a plurality of reinforcing angle irons or braces used in ordinary building construction. In Fig. 2 a

particular attention is directed to the fact that in constructing buildings in which the invention is to be embodied that the wall 2 is spaced sufficiently to permit the felt or other insulating medium to be placed in a continuous, unbroken line from floor to floor, and of uniform thickness throughout from the bottom to the top of the building. This is contrary to the general arrangement of directing and affixing such insulation in place, as such material is usually placed in a more or less winding line over the heads of columns and the like, and saves considerable time and labor and material.

It should also be understood that either one layer of insulation or several layers may be employed, and other minor differences made without departing from the spirit and intent of the invention.

What is claimed is:

1. A building including upper, lower and intermediate floors and ceilings, and walls spaced apart from the floors and ceilings, and a moisture-collecting and insulating medium on the walls extending in a uniform thickness from the bottom to the top of the walls and past the intermediate floors and ceilings, the insulating medium of the floors and ceilings being united with the insulating medium of the walls.

2. A building including upper, lower and intermediate floors and ceilings of concrete, and walls spaced apart from the concrete floors and ceilings, an insulating medium between the adjacent floors and ceilings, an insulating medium on the walls extending in a uniform thickness from the bottom to the top of the walls and past the intermediate floors and ceilings, the insulating medium between the adjacent floors and ceilings being united with the insulating medium of the walls, and inner coverings for the wall insulation and the concrete floors.

In testimony whereof we affix our signatures.

CLIFTON FON KNIGHT.
GEO. P. O'ROURKE.
